UNITED STATES PATENT OFFICE.

CARL D. BROWN, OF HOPEDALE, MASSACHUSETTS, ASSIGNOR TO DRAPER CORPORATION, OF HOPEDALE, MASSACHUSETTS, A CORPORATION OF MAINE.

TERRY LOOM.

Application filed November 21, 1925. Serial No. 70,504.

This invention relates to terry looms for weaving looped fabrics.

In looms of this general type there are usually two sets of warp threads employed, one for making the body of the fabric and termed the "body warps" and one for making the loops, called the "terry warps". During the weaving operation, in forming a terry fabric, it is the usual practice to 10 partially beat up the filling for a series of picks and then on a succeeding pick to fully beat up the filling, which thereupon draws upon the terry warps and forms pile or terry loops. The partial filling beat ups 15 above referred to are now ordinarily effected by either imparting to the lay alternating partial and full beat ups, or by the use of a swinging reed secured on the lay, movable to and from its full beat up position.

20 The invention is more particularly directed to the second class of terry looms, that is, looms employing a swinging reed. In such looms it is usual to actuate the reed either to or from its full beat up position by yielding means, such as a spring. This, however, is not always satisfactory because on beating up the terry loops with the reed in its full beat up position relative to the lay, considerable strain is placed upon the reed, which is very noticeable when the loom 25 is adapted to weave relatively wide terry fabrics or towels.

30 One of the purposes of the present invention is to provide a terry loom with a swinging reed which may be positively moved to and from its full beat up position and when either in full or partial beat up position may be locked in that position.

35 More specifically stated, the lay has a 40 swinging reed, and mounted upon the lay is a shaft having a positive connection with the loose reed, such that upon rocking movement of the shaft at intervals with respect to the movement of the lay, through a train 45 of mechanism, the reed may be positively moved to and from its full beat up position and locked in either position.

In the drawings:

50 Fig. 1 is a perspective view showing a loom provided with the present invention, only such parts being illustrated as are directly associated with the invention;

55 Fig. 2 is a perspective view with parts broken away, showing the lay provided

with the swinging reed and the connection 60 between the parts; and

65 Fig. 3 is an end elevation of the lay on an enlarged scale, showing more particularly the swinging reed and the eccentrics on the rock shaft and train of mechanism for 70 positively moving the reed to and from its full or partial beat up position.

75 Terry looms are usually provided with a train of mechanism including a terry arm which is actuated by a cam or pattern mechanism to determine the number of partial beat ups and the number of alternate beat ups of the loom, but as such mechanism is old in terry looms and the details thereof are not essential to the present invention, 80 such regular terry mechanism is not here shown.

85 The lay 1 is mounted on the usual lay swords 2, one at each end of the lay, and the lower ends of the lay swords are supported, as usual, on the lay rock shaft, to permit the lay to have movement towards and from the front of the loom. Any usual means may be employed to impart to the lay its beat up movements, and in the present invention the rear portion of the lay is connected to the pitman 3, one at each 90 end of the lay, which is regularly actuated by a crank shaft, as usual, to impart to the lay its beat up movements. As shown in Fig. 1, the pitman 3 is connected to the lay at the point 4, and, rising from the lay swords, one at each side of the loom, is the upwardly extending reed support 5 on which the bearings are mounted for pivotally supporting the reed. In the present instance, the uprising reed support 5 at each end of the lay has clamped thereto a bearing 6, the end portion 7 of which furnishes a bearing for the pivotal support 95 of the swinging reed. It is desirable sometimes to have the pivotal supports mounted for lateral adjustment, that is, adjustment in a direction towards and from the end of the lay, in order to adapt the parts for reeds of varying lengths, and as herein shown, the bearing 6 extends across the face of the reed supports 5 at each side of the loom, as at 8, and is clamped in place by the clamping member 9, which may be formed as shown 100 and held to the reed support 5 by means of the bolt 10.

105 The reed support frame comprises the

end members 11, the upper end portions of which are provided with the slotted arms 12 whereby the upper rail 13 of the swinging reed may be secured adjustably to the reed frame by means of the bolts 14 preferably provided with wing nuts 15. Each of the end members 11 has extending from its upper end a lug 16, which in the present instance is shown as provided with a pin 17 which furnishes a pivotal member for the reed as a whole. It is understood, of course, that the parts just described for pivotally supporting the reed are duplicated at each end of the lay. 15 The lower member 18 of the swinging reed is provided with the usual groove 19 to receive the lower portion of the reed 20, which may be of any usual or desired structure, and extending rearwardly from the lower member 18 of the reed frame are the projections 21 to each of which is secured a bearing 22, as indicated in Fig. 2. The means for securing the parts just described together may be of any usual character, such as the bolts 23, and, as shown, the bearings 22 are open, that is, the space 24 between the front and rear leg portions of the bearing is open for the ready reception of means to be presently described for positively actuating the reed to swing to either its full beat up position or to its partial beat up position, and lock it in either position. 20 In accordance with the present invention, the lay is provided with a shaft extending lengthwise of the lay, and offset or eccentric portions secured to the shaft engage the bearings extending from the reed frame, the construction being such that upon rocking movement of the shaft, the reed will be given its positive swinging movements and locking function, as hereinbefore stated. 25 The shaft above described preferably comprises the rock shaft 25, the end portions of which are supported in brackets at each end of the lay. As indicated in Fig. 1, the bracket 26 for supporting one end of the shaft 25 has the horizontally extending arm and the upwardly extending web 27 which may be secured to the reed support 5 by means such as the bolt 28 and the previously described bolt 10. So far as this feature of the invention is concerned, of course, the brackets may be variously contrived, their function being to provide means connected to the lay for properly supporting the shaft 25 for rocking movement. 30 The shaft 25 has secured thereto at spaced points along the same the eccentrics or offset portions 29, of which there may be any suitable number in accordance with the length of the reed, and each of the offset or eccentric portions 29 is received within one of the open bearings 22 projecting from the lower rail of the reed, the construction being such that should the shaft be rocked in one direction it will positively swing the reed to its full beat up position upon its pivotal support 17, and upon rocking movement in an opposite direction will swing the reed positively to its partial beat up position. 35 The construction of the means for shifting the reed upon the lay is such that the reed is held by positive, non-yielding means in either its partial beat-up or full beat-up position. 75 The horizontal portion of the bracket 26 is preferably extended rearwardly, as at 30, and pivotally supported thereon, as at 31, is a toothed segment 32, the teeth 33 of which are in engagement with the teeth of a gear 34 secured to the shaft 25, the effect being that upon rocking movement of the toothed segment 32, the shaft 25 will be positively rocked. 80 Appropriate rocking movements are imparted to the toothed segment 32 at times through the terry motion which is common in terry looms, and comprises usually a cam or pattern actuated through a lever to cause the production of the partial and full beat ups alternately. The segment 32 is provided with an opening 35 in which is pivotally supported at 36 the upper end portion of the rod 37, the lower end portion of which is connected to the regular terry arm, it being understood that the terry arm is given a movement at intervals with respect to the movement of the lay under the dictates of an appropriately shaped cam on the under side of the loom. 85 The lay 1 is cut away at 38, shown in Figs. 2 and 3, and a race plate 39 has its rear edge 40 so positioned with respect to the reed that when the latter is in its full beat up position, as indicated by full lines 100 Figs. 2 and 3, the dents of the reed will bear against the rear edge of the race plate, or approximately so. 90 The lay 1 is cut away at 38, shown in Figs. 2 and 3, and a race plate 39 has its rear edge 40 so positioned with respect to the reed that when the latter is in its full beat up position, as indicated by full lines 105 Figs. 2 and 3, the dents of the reed will bear against the rear edge of the race plate, or approximately so. 95 From the construction described as one good practical form of the present invention, it will be apparent that the swinging reed is under positive control of means to move it to and lock it in its partial beat up position, as shown by dotted lines in Fig. 3, for a desired number of picks, and then to move it positively to its full beat up position, as indicated by full lines in Fig. 3, to thereby produce the terry loops. The lay itself is given its usual uniform and unvarying movements towards and from the front of the loom, while the swinging reed effects the formation of the terry fabric. Of course the reed may be held in its partial beat up position for any desired number of picks, and, indeed, it may be moved to and locked in its full beat up position for a desired number of picks should a plain portion of fabric be desired at different points lengthwise of the fabric. In any event, the reed is under positive control at all times, both during its 110 115 120 125 130

movements to and from its full beat up position, and is locked in both its full beat up position and in its partial beat up position, a condition which is especially advantageous 65
 5 where wide terry fabrics are being woven, and as contributing to the production of such wide terry fabrics, the organization and construction hereinbefore described provides that the swinging reed may be positively 70
 10 connected to its actuating means to produce the terry loops at any desired number of points in the length of the reed.

What is claimed is:

1. In a loom for weaving terry fabrics, 15 the combination of the lay mounted for movement towards and from the front of the loom, a reed pivotally connected to the lay, a shaft mounted upon the lay and having eccentric portions connected to the reed 20 for successively and positively moving the reed to partial beat-up position and full beat-up position and locking the reed in each of the two positions, and means for actuating said shaft periodically.
2. In a loom for weaving terry fabrics, 25 the combination of the lay mounted for movement towards and from the front of the loom, a swinging reed and a rock shaft mounted on the lay, eccentric connections 30 between the rock shaft and swinging reed at different points in the length thereof, and means for rocking the rock shaft in relation to the lay to successively move the reed to partial beat-up position and full beat-up 35 position and lock the reed in each of said positions.
3. In a loom for weaving terry fabrics, 40 the combination of the lay, a swinging reed mounted thereon, a rock shaft mounted on the lay, positive connections between the swinging reed and rock shaft, and means for positively holding the reed in either of two positions while the lay moves back and forth, and operable to rock the rock shaft 45 at intervals relative to the lay movement that the reed may be positively moved to and locked in its partial beat up position and then positively moved to and locked in its full beat up position to form terry loops.
4. In a loom for weaving terry fabrics, 50 the combination of the lay having a swinging reed, reed positioning means carried by the lay, positive connection between the reed and positioning means and operable to hold 55 the reed in either of two positions while the lay moves back and forth, and an actuator for operating said positioning means at intervals relative to the lay movement to positively move the reed to and lock it in its 60 partial beat up position and then positively move it to and lock it in its full beat up position to form terry loops.
5. In a loom for weaving terry fabrics, 65 the combination of the lay having a swing-
- ing reed, a shaft on the lay having eccentric 70 connections with the reed at each end thereof and at a point between its ends, and means for rocking the shaft at intervals relative to the lay movement to move the reed positively to and from its full beat up position and positively lock the reed in each of said positions.
6. In a loom for weaving wide terry fabrics, 75 the combination of the lay having a swinging reed, a shaft on the lay having eccentric portions located at different points along its length and connected to the swinging reed, and means for rocking the shaft to positively move the reed to and from full beat up position.
7. In a loom for weaving terry fabrics, 80 the combination of the lay having a swinging reed provided with lugs extending from its lower portion at different points across the loom, a shaft having eccentric portions 85 positioned along its length to engage with said lugs for positively moving the swinging reed and locking it in full and partial beat up position relative to the lay, and means for rocking said shaft at intervals 90 during weaving to cause the reed to form terry loops.
8. In a loom for weaving terry fabrics, 95 the combination of the lay provided with a swinging reed, adjustable pivotal supports for the reed, a shaft mounted on the lay and having off-set portions connected to the reed for swinging it positively to its partial and full beat up positions relative to the lay, and locking it in each of said positions, a 100 terry rod actuated at intervals relative to the lay movement, and connections between the terry rod and said shaft to rock the shaft in one direction to swing the reed positively to its partial beat up position and 105 lock it there for a number of picks and then rock the shaft in the opposite direction to swing the reed to full beat up position and lock it there to form terry loops.
9. In a loom for weaving terry fabrics, 110 the combination of the lay having a regular beat up movement, a swinging reed carried by the lay and having open bearings disposed at different points across the loom and extending from the lower portion of the reed, a shaft mounted on the lay and having eccentric portions at different points along its length which are engaged by the open bearing of the swinging reed, and means for 115 actuating the shaft at intervals relative to the lay movement to move the reed positively to partial beat up position for a number of picks and then to full beat up position to produce terry loops.

In testimony whereof, I have signed my 125 name to this specification.

CARL D. BROWN.
